INVENTOR
John B. Hadaway,
By his attorneys,
Phillips & Alderson.

UNITED STATES PATENT OFFICE.

JOHN B. HADAWAY, OF BROCKTON, MASSACHUSETTS.

CHANNEL-FLAP-LAYING AND BOTTOM-CLEANING MACHINE.

SPECIFICATION forming part of Letters Patent No. 633,886, dated September 26, 1899.

Application filed April 26, 1898. Serial No. 678,865. (No model.)

To all whom it may concern:

Be it known that I, JOHN B. HADAWAY, a citizen of the United States, residing at Brockton, in the county of Plymouth and State of Massachusetts, have invented certain new and useful Improvements in Channel-Flap-Laying and Bottom-Cleaning Machines; and I do hereby declare the following to be a full, clear, and exact description of the invention, such 10 as will enable others skilled in the art to which it appertains to make and use the same.

As boots and shoes are now commonly manufactured after the sole has been stitched to the lasted upper and insole and the channel-flap has been turned back over the channel to cover the out seam an operation commonly called "laying" the channel-flap before the shoe is taken to the "beating-out" or "leveling" machine, which imparts to the sole its 20 final shape and set, it is necessary that the bottom of the sole should be cleaned to remove any dust, particles of wax, or other foreign substance which would be rubbed into the sole by the action of the leveling-machine.

25 The operation of cleaning the bottom of the sole has heretofore in so far as I am advised of the state of the art been performed as a separate and distinct operation from the channel-flap-laying operation and commonly by a 30 rotary brush or other suitable device applied to the shoe after the channel-flap-laying operation has been completed.

The object of the present invention is to 35 provide a machine embodying channel-flap-laying mechanism and bottom-cleaning mechanism arranged to coöperate with each other to produce at a single operation from a shoe with an unlaid channel-flap a clean smooth sole ready for the leveling operation; and to 40 the above end the present invention consists of the combination, with channel-flap-laying mechanism, of a bottom-cleaning device, as hereinafter more fully described in this specification and pointed out in the claims, the 45 accompanying drawing illustrating a preferred form thereof.

The single view of the drawing shows all essential features of a device embodying the present invention, the view being taken partially in section and partially in elevation.

50 In the drawing, A represents a disk or wheel which is rotated by the shaft a and

which is provided with a rim a', from which are radially projected the channel-flap-laying blades a². As shown, the disk or wheel A is 55 arranged to yield laterally and torsionally to prevent the blades a² from injuring the sole during the operation of the machine.

The construction of the disk A and its actuating mechanism and the means for rendering it laterally and torsionally yielding may be 60 and conveniently are the same as heretofore fully disclosed by me in Letters Patent No. 576,114, issued February 2, 1897, and no further description thereof is deemed necessary 65 herein. I may say, however, that the present invention is by no means limited to devices above referred to or to any specific form of channel-flap-laying mechanism, such mechanism being susceptible of great variation in 70 construction, organization, and mode of operation without involving any departure from the present invention.

Returning to the specific form of my invention illustrated in the drawing, the bottom-cleaning mechanism consists of an annular brush B, secured to the disk A and which projects between the blades a² in position to act upon the sole simultaneously therewith. The brush proper may be made of bristles b 75 of any suitable material and, as shown, is provided with the annular back b', preferably of wood, which is secured by a series of screws b² in an annular angle-piece b³, which is secured by a series of bolts b⁴ to the rim a'. In 80 order that the brush B may be adjusted to properly position its working parts with reference to the blades a², I have in the form of my invention illustrated arranged the bolts b⁴ to engage slots a⁴ in the rim a', so that by 85 loosening the bolts b⁴, the brush B may be set to project as required beyond the working parts of the blades a² and by setting up the bolts b⁴ clamped in the desired position.

In using my improved channel-flap-laying 95 and bottom-cleaning machine the operator presents the shoe thereto in substantially the same manner that the shoe is presented to my said patented machine and by the combination of devices heretofore described lays the 100 channel and cleans the bottom of the sole at a single operation and in substantially the same time required to lay the channel.

Having thus described my invention, I

claim as novel and desire to protect by Letters Patent—

1. In a channel-flap-laying and bottom-cleaning machine, the combination with channel flap-laying mechanism, of a bottom-cleaning device arranged to coöperate therewith to simultaneously lay the channel-flap and clean the bottom of the sole of a boot or shoe, substantially as described.

10. 2. In a channel-flap-laying and bottom-cleaning machine, the combination with chan-

nel-flap-laying mechanism, of a bottom-cleaning brush arranged to coöperate therewith to simultaneously lay the channel-flap and clean the bottom of the sole of a boot or shoe, substantially as described. 15

In testimony whereof I affix my signature in presence of two witnesses.

JOHN B. HADAWAY.
